UNITED STATES PATENT OFFICE.

THOMAS PARKINSON HAYDOCK, OF NEW BEDFORD, MASSACHUSETTS.

PICKER-STICK-CUSHIONING MEANS.

1,392,154.

Specification of Letters Patent. Patented Sept. 27, 1921.

Application filed June 8, 1921. Serial No. 475,982.

To all whom it may concern:

Be it known that I, THOMAS P. HAYDOCK, a citizen of the United States, residing at New Bedford, in the county of Bristol and 5 State of Massachusetts, have invented new and useful Improvements in Picker-Stick-Cushioning Means, of which the following is a specification.

The object of my present invention is 10 the provision of a cushioning means for picker sticks of looms, characterized by simplicity, inexpensiveness and the facility with which the cushion may be removed and replaced with a fresh cushion when occasion 15 demands.

To the attainment of the foregoing, the invention consists in the improvement as hereinafter described and definitely claimed.

In the accompanying drawings, forming 20 part of this specification:—

Figure 1 is an elevation illustrating a right hand cushioning means constructed in accordance with my invention as properly positioned on a right hand shuttle box.

25 Fig. 2 is an enlarged vertical section showing my novel cushioning means *per se*.

Fig. 3 is an enlarged section on line 3—3 of Fig. 1.

30 Figs. 4 and 5 are perspectives of the device body.

Similar numerals of reference designate corresponding parts in all of the views of the drawings.

In Fig. 1 I show my improvement as applied to a right hand shuttle box, but it 35 will be understood in this connection that the improvement is also applicable to a left hand shuttle box in which latter event the parts of the body will be arranged to accommodate it to a left hand shuttle box.

The improvement comprises a body and a cushion. The body is preferably though not necessarily in the form of a casting and comprises a shank 16 in which is an aperture 17, an upright post 19 on the shank, a 45 pocket portion 21 at the end of the shank opposed to the picker stick 12, and a flange 27 that reaches above the pocket portion 21 and one side edge of the shank 16 as illustrated. The bottom wall of the pocket portion 21 is rounded and in the said pocket portion 21 adjacent to the post 19 is provided a shoulder 24. The said pocket portion 21 adjacent to the picker stick 12 is 50 bifurcated as indicated by 22 and 25, for the reception of the picker stick and to en-

able the picker stick to bring up against the cushion in the pocket portion 21 of the body.

The cushion indicated by 23 may be 60 formed of a strip of leather, which may be split, if desired, so as to increase its flexibility. I would have it understood, however, that the said cushion may be made of any other appropriate material such as old 65 or new rubber hose, an old tire casing, rope or any other available material possessed of cushioning capacity. The cushion is arranged in the pocket portion 21 of the body through the mouth 26 of said pocket portion so that its edges will be opposed to and held against the underside of the shuttle box.

When my novel cushioning means is applied in the manner indicated it will be understood that the body of the improvement will be strongly held in position by a bolt 18 and a nut thereon, the said bolt being passed through the aperture 17 in the shank 16. It will also be understood that the post 70 19 will rest in the slot in the bottom of the shuttle box while the flange 27 will rest against the side of the shuttle box to preclude lateral shifting of the cushioning means. When the body is applied as stated 75 the shoulder 24 in the body will operate to hold the cushion 23 under pressure against the underside of the lay 10 while the bifurcation in the pocket will enable the picker stick 12 to act against the cushion 23 so that the 80 cushion will absorb the shock and jar.

Manifestly when the cushion 23 is impaired by wear, the body may be expeditiously and easily removed for the placing of a fresh cushion therein and may then as 85 readily be attached to the lay.

The picker stick is shown in Fig. 1 as equipped with appurtenances 13, 14 and 15. These appurtenances are of the common types well known in the art, and need not, 100 therefore, be described.

I have entered into a detailed description of the construction and relative arrangement of parts embraced in the present and preferred embodiment of my invention in order 105 to impart a full, clear and exact understanding of the said embodiment. I do not desire, however, to be understood as confining myself to the said specific construction and relative arrangement of parts inasmuch as 110 in the future practice of the invention various changes and modifications may be made

such as fall within the scope of my invention as defined in my appended claims.

Having described my invention, what I claim and desire to secure by Letters-Patent, is:—

1. Picker stick cushioning means comprising a holding body having an apertured shank, a post rising from said shank, a pocket portion at one end of the shank and bifurcated for the reception of a picker stick, a shoulder in said pocket portion adjacent to the post, and a flange extending upwardly from the pocket portion and one side edge of the shank, and a cushion removably arranged in said pocket portion of the body; said cushion being shaped into rounded form and being adapted to be held by the body against the opposed portion of a loom.
- 10 2. A body adapted to hold a picker stick cushion and to be attached to a loom portion; the said body having a pocket in one
- 15
- 20

end and also having the said end bifurcated, and further having an apertured shank, a post thereon to form an abutment for a cushion, and a side flange.

3. Picker stick cushioning means comprising a body in which is a pocket open at its upper side to confine a cushion against an opposed loom portion, the end of said pocket being bifurcated to enable a picker stick to act against the cushion, and the inner and upper portion of the pocket being shoudered.

4. In picker stick cushioning means, the combination with a body having a pocket and a bifurcation in the end wall of the pocket, of a cushion of appropriate material reduced to hollow rounded form and removably arranged in the pocket to be confined by the body against an opposed loom portion.

In testimony whereof I affix my signature.
THOMAS PARKINSON HAYDOCK.
